ENHANCING PRECIPITATIONS BY APPLYING SOLUBLE COMPLEX FLUORINE-CONTAINING REAGENTS

Glenn W. Stahl, Richland, Wash., assignor to the United States of America as represented by the United States Atomic Energy Commission

No Drawing. Application June 4, 1945
Serial No. 597,593

16 Claims. (Cl. 23—14.5)

This invention relates to a procedure for the processing of materials containing the element of atomic number 94, known as plutonium, for separating the plutonium from extraneous matter such as substances of the kind present in neutron irradiated uranium as exemplified by uranium and especially fission products, and the like radioactive contaminants. More particularly, this invention concerns a separatory and concentration procedure involving the use of supplemental additions, such as fluosilicic acid, whereby improved decontamination and Pu recovery may be obtained.

As described herein, the isotope of element 94 having a mass of 239 is referred to as 94^{239} and is also called plutonium, symbol Pu. In addition the isotope of element 93 having a mass of 239 is referred to as 93^{239} . Reference herein to any of the elements is to be understood as denoting the element generically, whether in its free state or in the form of a compound, unless indicated otherwise by the context.

Elements 93 and 94 may be obtained from uranium by various processes which do not form a part of the present invention including irradiation of uranium with neutrons from any suitable neutron source, but preferably the neutrons used are obtained from a chain reaction of neutrons with uranium.

Naturally occurring uranium contains a major portion of $_{92}U^{238}$, a minor portion of $_{92}U^{235}$, and small amounts of other substances such as UX_1 and UX_2 . When a mass of such uranium is subjected to neutron irradiation, particularly with neutrons of resonance or thermal energies, $_{92}U^{238}$ by capture of a neutron becomes $_{92}U^{239}$ which has a half life of about 23 minutes and by beta decay becomes 93^{239} . The 93^{239} has a half life of about 2.3 days and by beta decay becomes 94^{239} . Thus, neutron irradiated uranium contains both 93^{239} and 94^{239} but by storing such irradiated uranium for suitable period of time, the 93^{239} is converted almost entirely to 94^{239} .

In addition to the above-mentioned reaction, the reaction of neutrons with fissionable nuclei such as the nucleus of U^{235} results in the production of a large number of radioactive fission products. As it is undesirable to produce a large concentration of these fission products which must, in view of their high radioactivity, be separated from the 94^{239} and further as the weight of radioactive fission products present in neutron irradiated uranium is proportional to the amounts of 93^{239} and 94^{239} formed therein, it is preferable to discontinue the irradiation of the uranium by neutrons when the combined amount of 93^{239} and 94^{239} is equal to approximately 0.02 percent by weight of the uranium mass. At this concentration of these substances, the concentration of fission elements which must be removed is approximately the same percentage.

A number of processes have already been proposed for

2

accomplishing the separation and concentration of Pu. Certain of these processes are generically known as the "bismuth phosphate" type process and the "wet fluoride" type of process. These processes are the invention of others and the processes are described in co-pending applications, as for example application Ser. No. 519,714, now Patent No. 2,785,951, to be referred to hereinafter, which gives details relative to such processes.

It is sufficient to indicate at this point that by means of such processes, of which there are a number, applied in one or several cycles dependent upon the concentration of contaminants and similar considerations the contamination may be substantially reduced and the plutonium recovered. That is, as described above, the desired plutonium to be recovered is in the presence of substantial quantities of fission products evidenced by beta and gamma activities, and the plutonium must be isolated from at least a portion of the activity. In other words, the activity preferably is eliminated either completely or at least to a certain tolerance level so that the Pu may be handled or further used without danger from radioactivity due to contaminants. The bismuth phosphate method of by-product and product precipitation is generally illustrative of processes which may be applied to separate and recover plutonium.

Thus while existing processes, including the bismuth phosphate type of process, are quite efficient and successful, it may be necessary to repeat the decontamination cycles a number of times in order to obtain a Pu in which the activity has been eliminated or reduced to the tolerable amount. As set forth in application Serial No. 519,714, filed January 26, 1944, of Thompson and Seaborg, now Patent No. 2,785,951, it has been discovered that plutonium has more than one oxidation state, including a lower oxidation state or states referred to herein as $Pu^{(r)}$ in which the element is characterized by forming insoluble phosphates and other insoluble compounds and a higher oxidation state or states referred to as $Pu^{(o)}$ in which the element forms soluble phosphates and other soluble compounds.

That is, by having the metal as $Pu^{(r)}$, a product precipitation or extraction may be accomplished in which a carrier precipitate such as, for example, bismuth phosphate brings down the $Pu^{(r)}$ leaving behind in solution a substantial portion of fission products and other sources of contamination. However, some of the activity in the form of contaminants such as barium, columbium, zirconium, and lanthanum activities may be carried down with the $Pu^{(r)}$ and may be quite difficult to separate from Pu. Further the amount of these latter fission products could be reduced by a decontamination cycle consisting of a by-product precipitation and a product precipitation using, for example, $BiPO_4$ as a carrier.

For carrying out such a cycle, a carrier precipitate containing $Pu^{(r)}$ and activity from the first extraction, or from a previous product precipitation, after suitable dissolution, may be oxidized so that $Pu^{(o)}$ is obtained. The $Pu^{(o)}$ remains in solution and a by-product carrier precipitate, such as a bismuth phosphate by-product precipitate, under the oxidizing conditions can carry down fission products leaving the $Pu^{(o)}$ in solution. However, in this step certain by-product precipitate fines may not separate out or otherwise some contamination may remain so that the solution remaining which contains the $Pu^{(o)}$ may still be contaminated with some fission products although in much smaller amounts. It should be kept in mind that since the Pu is in an environment of radioactivity which may give many millions of counts a

minute per milligram of fission product present, that the clean-cut separation of the Pu presents considerable difficulty.

To complete this decontamination cycle, the Pu^(o) may be reconverted to Pu^(r) and the first product precipitation carried out leaving behind substantial portions of the remaining fission products.

Thus a process may be devised consisting of an extraction step and one or more decontamination cycles.

In order to illustrate my invention and some of the points where the invention has particular value, a typical process is described below.

The illustrative processes are fully described in the co-pending applications of Thompson and Seaborg, Ser. Nos. 478,570 (now Patent No. 2,799,553), and 519,714 (now Patent No. 2,785,951), filed March 9, 1943, and January 26, 1944, and may be outlined generally as follows:

RECOVERY PROCESS

(A) Product extraction:

(1) Metal solution step.

(2) Extraction of Pu from solution.

(B) Decontamination cycle:

(1) By-product precipitation step—

(a) With scavengers, or

(b) Without scavengers.

(2) Product precipitation step.

For convenience, in reference the following brief description of the illustrative process is made in accordance with the above outline.

(A) Product extraction:

(1) Metal solution step—

Neutron irradiated uranium is dissolved in a suitable quantity of 60-70% nitric acid. This gives a uranyl nitrate solution containing Pu^(r) and Pu^(o).

(2) Extraction from metal solution—

The solution is subjected to treatment with an agent such as sodium nitrite, formic acid, H₂O₂, oxalic acid or the like in excess for a period of about one hour at a temperature from 50° C. to 75° C. whereby any of the Pu metal, some of which may have been oxidized to the Pu^(o) state in the solution step, is reduced to the Pu^(r) state, hydrazine is eliminated or other action takes place. The uranyl nitrate concentration of the solution is adjusted to 20% based on uranyl nitrate hexahydrate and under existing practice H₂SO₄ is added. To the solution is now added a source of bismuth ion to provide a concentration of bismuth ion equivalent to 10 grams of Bi⁺³ ion in four liters thereof. Phosphoric acid is also added to make the solution between 3-8 M therein, and a precipitate comprising BiPO₄ which carries the Pu^(r) comes down and is separated from the solution by filtration or centrifugation. This illustrates the extraction or product precipitation from a uranyl nitrate solution.

(B) Decontamination cycle:

(1) By-product precipitation step—

The BiPO₄ precipitate from the Extraction Step which carries the Pu^(r) is dissolved in 10 N HNO₃. The acidity of the solution is reduced to 6 N HNO₃ by dilution and the solution made 0.01 M in NaBiO₃. Various other oxidizing agents, such as potassium dichromate, permanganate, and the like, may also be used. Another oxidant such as potassium dichromate, may be added in connection with the primary oxidant, sodium bismuthate, to hold the Pu^(o) in the oxidized state after all bismuthate has been reduced or decomposed. On heating the solution at 50° C. for 1 hour, the plutonium is oxidized to the Pu^(o) state. The solution is then diluted to 1 N acidity by addition of

water and H₃PO₄ added to provide a suitable concentration for causing the formation of a BiPO₄ precipitate. The solution is heated to about 75° and BiPO₄ precipitates and carries a large portion of fission products but not Pu^(o). The precipitate may be removed by filtration or centrifugation and discarded. This illustrates a by-product precipitation which leaves a solution of oxidized Pu^(o) and a smaller amount of fission products.

(a) Scavengers:

Prior to, during, or following this BiPO₄ by-product precipitation step, a procedure termed "scavenging" may be carried out. Scavenging involves the formation of a second or third by-product precipitate consisting of substances other than BiPO₄ for carrying these activities, such as zirconium, columbium, cerium and barium which are not, or would not be, removed completely from Pu^(o) solutions by the ordinary BiPO₄ by-product precipitation step above described. For example, the zirconium activity can be precipitated as zirconium phosphate by adding zirconium phosphate to the solution of oxidized Pu^(o) and fission products. Other examples and a more complete explanation of "scavenging" are disclosed in the co-pending application of Glenn T. Seaborg, Stanley G. Thompson, and Norman R. Davidson, Ser. 713,906, filed December 4, 1946. The scavenger precipitates may be discarded after separation by filtration, centrifugation and the like.

(2) Product precipitation—

After the by-product precipitation step, with or without scavengers, the Pu^(o) is reduced by adding a suitable concentration of Fe⁺⁺ ion and heating the solution to 75° C. for 1 hour. The reduction of Pu^(o) to Pu^(r) also may be accomplished by using, instead of Fe⁺⁺, any of a number of reducing agents of which sulphur dioxide, hydrogen peroxide, sodium nitrite, oxalic acid and the like are mentioned for illustration.

To the solution of Pu^(r) is now added a source of bismuth ion to provide a concentration of bismuth ion equivalent to 10 grams of Bi⁺³ ion in four liters of solution. Phosphoric acid is also added to make the solution between 0.30 M and 1.20 M therein. A precipitate, comprising BiPO₄ which carries Pu^(r) comes down and is separated from the solution. This completes the product precipitation step and the decontamination cycle which consists of the by-product precipitation step and product precipitation step.

REPEATED CYCLES

If it is desired to remove additional fission products from the Pu obtained from the foregoing procedure, the decontamination cycle may be repeated therewith, beginning with the solution of the BiPO₄ product precipitate in nitric acid, followed by oxidation and the other decontamination cycle steps above described. This decontamination cycle may be repeated as often as desired, depending upon the desired degree of elimination of fission products.

The exact manner of obtaining the bismuth phosphate product and by-product precipitates or other carrier precipitates is not a limitation on the present invention.

Various amounts and sources of bismuth and phosphate ions may be used. Details respecting these aspects are described in other co-pending applications and form no integral part of the present invention. Consequently, in certain of the description which follows, reference will merely be made to a product or by-product carrier, or similar terms used, it being apparent that such carrier may be formed in any suitable manner, one of which methods has been illustrated above.

As mentioned, in all existing processes, including the

BiPO_4 process above described, separation of Pu from fission products is not clean cut. For example, in the extraction of Pu from a uranyl nitrate solution, the BiPO_4 carries practically all of the product but also some of the fission activity. Likewise, in the by-product precipitation, with or without scavengers, the by-product precipitate does not carry all of the fission activity but leaves some fission activity in solution with the oxidized Pu.

In the separation of the by-product precipitate, whether by centrifugation, filtration, or other means, some of the finely divided by-product precipitate containing fission activity passes the centrifuge, filter or other means, and thus is carried over into the product precipitation step. The presence of these residues of fission activity from the by-product precipitation during product precipitation has been found to diminish materially the decontamination of the Pu obtained in the product precipitation step.

I have found that the aforementioned separatory and recovery processes which are referred to herein as existing, standard or conventional processes, exemplified by the bismuth phosphate process, may have included therein certain supplemental agents and operations for improving such processes.

The present invention is supplemental to the existing processes and is designed to obtain more clean cut separations, a more favorable decontamination factor in fewer steps or cycles, or a higher decontamination factor, namely, more complete decontamination than formerly was possible by the particular process, in the same number of steps, and to effect a higher recovery of Pu.

The meaning of the terms, contaminants, bismuth phosphate type of process, product and by-product precipitate, decontamination, and similar terms are apparent to some extent from the preceding description and will be further apparent as the description proceeds.

The invention has for one object, to provide improvements in methods for the separation and recovery of plutonium.

Another object is to provide a method of separating plutonium by a procedure wherein certain additional materials and steps supplemental to or in place of those heretofore used are employed.

Another object is to provide an improved procedure for eliminating, eradicating, or lessening gamma contamination.

Another object is to provide improved procedures in forming by-product and product carrier precipitates, and in improving other phases of recovery processes.

Still another object is to provide a procedure for improving decontamination.

Still a further object is to improve decontamination and product recovery by steps and addition materials which lend themselves to combination with steps already known or practiced.

Another object is to provide a type of process which may employ materials used in existing processes, but with more effective decontamination, and which may be carried out in existing equipment without change, or with a minimum of equipment change.

Still another object is to improve existing procedures by reducing the number of cycles required for decontamination or by obtaining higher decontamination with the same number of cycles.

Another object is to provide a process susceptible of treating sources of Pu containing concentrations thereof and activities higher than heretofore encountered.

Other objects will appear hereinafter.

I have confirmed that Pu in admixture with various extraneous materials may be separated and concentrated by the use of the series of steps involving the formation of certain carrier precipitates, as above described. The formation of these precipitates may be similar to existing practices in many features as respects some of the reagents, temperatures and similar aspects.

I have found that processes of the aforementioned types

involving the use of precipitates for carrying contamination away from Pu and carrying Pu away from contamination may be improved at many points, from the extraction step to the product precipitation step, and even to the step of cleaning out the equipment, by use of fluosilicic acid type reagent as set forth in detail herein.

For example by the carrying out of extraction under the conditions of the present invention not only are the advantages of the prior processes retained but additional advantages, such as the precipitation of less barium, zirconium and columbium in this step are obtained.

The present invention comprises the use of fluo-reagents in processes of recovery of transuranic elements, such as Pu, for the purposes of effecting a better separation of fission products and of increasing the yield of the transuranic elements.

More specifically the present invention comprises the use of fluo-reagents for the purpose of complexing zirconium, columbium and uranium so that they can be removed from solutions or materials in which they are contained along with other material from which it is desired to separate them, and which, if the solution or material is radioactive, results in the removal of fission products.

The solutions containing Pu which may be treated by my invention may be the same type of solutions as heretofore treated, or may be solutions in which the concentrations of components are much higher.

As apparent from the foregoing, one common type of solution containing Pu subject to separation and recovery procedures comprises a nitric acid containing liquid having a content of Pu therein. The nitric acid solution also contains other materials, such as radioactive materials, of which the procedure of the present invention aids in the elimination or reduction.

I have found that certain supplemental fluo-reagents, such as fluosilicic solid addition to a solution containing the $\text{Pu}^{(r)}$ and a carrier in the above extraction and product precipitation steps, causes the Pu to be carried away from extraneous matter more effectively. I have further found that this action of fluosilicic acid and other comparable compounds in giving better separation, better decontamination, and complexing or solubilizing of radioactivity has numerous other applications in separation and recovery processes of the class described.

Broadly, therefore, my invention may be applied to various solutions and particularly solutions containing high activities. The solutions to be processed by my invention have added thereto such reagents as may be required, dependent upon the particular composition and condition of the solution, to obtain the customary carrier precipitate formation at that particular phase of the process. Before, simultaneously therewith, or thereafter, as will be further apparent from the several examples, there is applied thereto the procedure of the present invention for causing improved separation and particularly the elimination of gamma activity.

I have found that by using fluosilicic acid or comparable compound, that processes for the recovery of Pu may be materially improved. I have found that fluosilicic acid may be employed in numerous different ways. In general, compounds of a formula H_xMF_y may be employed, examples of such other compounds being the acids of titanium, boron and tin, more specifically exemplified by fluostannic or fluotitanic acid. In the formula H_xMF_y , H represents hydrogen, ammonium, or other metallic or metalloid ions.

In further detail, examples of some of the uses of fluosilicic acid are as follows: In the present extraction step, such as step (2) above, it is usual to add a content of sulfate ion for complexing U as already briefly indicated above. However, this addition of sulfate ion may be disadvantageous in that it may precipitate a certain amount of barium activity. It has been found that the addition of fluosilicic acid in place of or in conjunction with sulfuric acid not only complexes the U, but lowers

7
the barium, zirconium and columbium activity precipitated. Also, the use of fluosilicic acid is less critical than in sulfuric acid and may be employed in uranyl nitrate solutions, as for example of a 15% to 40% concentration and at temperatures as low as 35° C.

In the extraction step, fluosilicic acid or a like agent is added alone or in conjunction with a partial addition of sulfuric acid, the amount of either or both acids being sufficient to complex in a soluble form at least one fourth of the U present in the solution. The acids may be added up to an amount such that the total acid is about 25% in excess of that required to complex the U, in which case the fluosilicic acid preferably should be about 50% to 100% of the total acid.

It is preferred, however, to use fluosilicic acid only and in an amount which will completely complex U.

I have also found that the addition of fluosilicic acid renders the active columbium and zirconium phosphates soluble and thereby prevents them from following the bismuth phosphate product precipitate in the above extraction step, thereby giving a higher decontamination. In addition to adding fluosilicic acid for rendering soluble the active zirconium and columbium materials, this procedure may be supplemented by adding inactive zirconium and columbium compounds. While the addition of fluosilicic acid substantially reduces the carrying by carrier precipitates of the zirconium and columbium activity, a small amount of this activity may still be carried by the bismuth phosphate precipitate. By adding, in addition to the fluosilicic acid, inactive potassium or ammonium fluozirconates which dilute the active fission products a still higher decontamination factor may be obtained.

Certain recovery processes for the waste liquors from the extraction step containing uranium and fission products may be carried out employing fluosilicic acid. It also appears that certain precipitates such as the sodium and potassium fluosilicates will carry fission products but not carry the uranium, thus permitting recovery of U free from fission products.

The present invention thus far is described in connection with extraction step (2) above. In addition, it may be employed, as will be apparent from the specific examples which follow, in the product precipitation step, for improving decontamination and for lessening product loss.

Referring next to the use of the present invention in the product precipitation step such as above described, in the product precipitation step, the solution treated comprises a nitric acid solution of $Pu^{(o)}$ and fission activity which is the centrifugate resulting from the prior byproduct precipitation. To this oxidized solution, fluosilicic acid in amounts from 0.002 M up to an amount just insufficient to cause precipitation of a metallic fluosilicate, as for example sodium fluosilicate, may be added. The $Pu^{(o)}$ solution may then be reduced and a regular $BiPO_4$ product precipitate formed. Instead of fluosilicic acid, ammonium fluosilicate or other fluo-reagents may be used, and the particular fluo-reagent chosen may be added either prior to, during, or after reduction and/or prior to, during or after the $BiPO_4$ product precipitation.

The addition of the fluo-reagent in the product precipitation step increases decontamination as a result of complexing zirconium and columbium fission activity in a soluble form.

The improvement in decontamination through the use of fluo-reagents is so great that scavengers may be eliminated from the previous by-product precipitation step. The elimination of scavengers results in lower loss of Pu in the by-product precipitation step. Thus the use of fluo-reagents results in higher product recovery in both the by-product precipitation and product precipitation steps with no sacrifice in overall decontamination.

The above results are obtained regardless of whether

or not scavengers are used in the by-product precipitation step.

If scavengers, such as zirconium, columbium, or tantalum are used in the by-product precipitation step, 5 the scavenger fines passing through the centrifuge or filter are solubilized by the fluo-reagents. If these fines, which contain relatively high amounts of fission products, are not solubilized prior to product precipitation, decontamination is reduced since the product precipitate which carries Pu also carries the fines. When the fines are solubilized with fluo-reagents prior to precipitation of the product, the associated fission activity tends to remain in solution and is not carried in the product precipitate. Thus decontamination is improved 10 through the use of fluo-reagents.

Other beneficial effects of the use of fluo-reagents include lower product losses in the product precipitation and greater ease of centrifugation or filtration of the product carrier due to increased crystal size of the carrier.

15 It has also been found that a method may be carried out by the addition of fluosilicic acid for complexing various activities, wherein decontamination may be accomplished by repeated precipitations without the alternate oxidation and reduction procedure now used.

20 There are a number of miscellaneous operations which may be carried out, as for example: The decontamination of equipment may be accomplished by washing the equipment with fluosilicic acid.

25 It is also possible to wash crystals of precipitates with fluosilicic acid solution for removing surface contamination without substantial Pu loss.

30 A still further understanding of my invention will be had by reference to the following detailed examples.

35 In these examples the solutions containing Pu which were treated were, in general, the usual type encountered industrially, excepting that the gamma activity was in many instances perhaps higher than usual. That is, the solutions were obtained from standard processing and were approximately 1 normal in nitric acid, however, 40 the invention is not limited to this normality. The solutions also may contain residual reducing agents, oxidizing or various inorganic acid and the like ingredients in addition to extraneous material, such as high activities.

45 Reference is now made to these specific examples:

Example 1

In accordance with this example, the substitution of fluosilicic acid for sulfuric acid in the extraction cycle 50 for recovering Pu was carried out. As previously described uranyl nitrate solutions containing Pu , prior to the formation of a carrier precipitate therein, have heretofore been treated with sulfuric acid or other source of sulfate ion for complexing U. That is, the sulfate ion 55 prevents the U from precipitating along with the Pu with the carrier precipitates formed for carrying down the Pu . However, while the sulfate ion satisfactorily complexes U, presumably it has been the cause of a certain amount of barium precipitating along with the Pu . Since the 60 barium precipitating is strongly radioactive, the resultant Pu precipitate has been contaminated.

In accordance with the several runs carried out under this example, existing extraction procedure, as already 65 described, was followed excepting that in place of the addition of sulfate ion usually made, fluosilicic acid was incorporated. It was found that fluosilicic acid complexed the U in a manner comparable to the sulfate ion, that it did not cause the substantial precipitation of active barium and in addition complexed zirconium and columbium as well, both of which are sources of gamma radiation. Therefore, the resultant extraction evidenced 70 a higher decontamination factor in that the Pu material separated was freer of contamination. The results of runs under this example are summarized in the following 75 table:

TABLE 1

Run No.	Acid in Extraction	Percent La	Percent Zr	Percent Cb	Percent Ba	Gross Decontamination Factor
11	1 N H ₂ SO ₄	10.0	72.9	11.2	2.6	3.6
12	1 N H ₂ SiF ₆	16.2	69.2	10.5	.09	14.7
13	1 N H ₂ SO ₄	14	64.5	14	12	3.9
14	1 N H ₂ SiF ₆	21.7	63.7	11.7	.05	16

From the above table, which includes an analysis of the extraction precipitate, it can be seen that there is very much less Ba carried into the product (Pu) precipitate.

While in the preceding runs fluosilicic acid has been used to entirely replace the sulfuric acid addition, improved results may also be obtained by replacing only a part of the sulfuric acid by fluosilicic acid. It was also observed that while a uranyl nitrate solution having a concentration of 20%, based on uranyl nitrate hexahydrate, sulphuric acid addition, the concentration based on uranyl nitrate hexahydrate might vary from 10%-40% with satisfactory results when using fluosilicic acid. Also it was unnecessary to maintain the temperatures during the precipitation within particularly narrow ranges. When employing fluosilicic acid for complexing the extraction step may be carried out at temperatures varying from room temperatures to, for example, 85° C.

Example II

In accordance with this example, the use of fluosilicic acid as an auxiliary to scavenging was carried out. A standard uranyl nitrate solution containing Pu was treated in the runs under this example. Standard bismuth phosphate product and by-product precipitates of the type already described were applied to the solution, leaving a nitric acid solution containing Pu^(o). To this solution the usual cerium and zirconium phosphate scavenger precipitate was formed, the function of which was to carry down at least a part of the residual activity which had not been carried down by the aforementioned by-product precipitate.

In the separation of this cerium and zirconium scavenger precipitate industrially, centrifuges may not effect a complete removal of all of the finely divided residues. Consequently, when such scavenged solutions are thereafter reduced prior to making a product precipitate for carrying down Pu^(r), a certain amount of these fines may be carried down with the Pu^(r) thereby contaminating the Pu^(r) product with radioactivity.

In accordance with the present invention, it has been found that by adding a small amount of fluosilicic acid to the solutions remaining after centrifugation that these

TABLE 2

Solution Description	Fe ²⁺ , Mols	Conc. H ₂ SiF ₆ , Mols	Gamma Factor
Oxidized Solution after Ce-Zr scavenging	.03	0	4.5
Do	.03	.05	11.9
Do	.03	.025	10.0

As apparent from the table, an oxidized solution containing Pu was treated with Fe²⁺ as a reducing agent. Thereafter fluosilicic was added in accordance with the present invention. By making counts in conventional manner on the product precipitates the gamma decontamination factor may be obtained. As may be seen, where fluosilicic acid had been used the gamma factor was more than double that where no fluosilicic acid had been used.

Example III

In accordance with this example, several runs were carried out for utilizing fluosilicic acid as a substitute for scavengers. In the preceding example a scavenger step was included and after this scavenging the fluosilicic acid additions were made. However, in accordance with the present example, the scavenging was omitted and the fluosilicic acid additions were made to the solution remaining after the by-product precipitate had been taken. In all other respects the process and materials were in accordance with existing procedure. That is, a uranyl nitrate solution containing Pu was processed which had been treated by existing bismuth phosphate product and by-product precipitations to give a nitric acid solution Pu^(o). The Pu^(o) solution was then reduced with a ferrous reducing agent and a regular bismuth phosphate product precipitate formed in the presence of fluosilicic acid. The results and details of the several runs in accordance with this example are summarized below:

Run 1.—A straight BiPO₄ by-product precipitate was applied in both cycles; the by-product precipitate was digested at 75° C. for 30 minutes. A straight BiPO₄ product precipitation was applied in both cycles in presence of 0.05 M H₂SiF₆.

Run 2.—This run was the same as 1, except the by-product precipitate was digested at room temperature for 30 minutes.

Run 3.—In this run a PbSO₄ addition with BiPO₄ by-product precipitate was made in both cycles (by-product digested at 30 minutes at 75° C.). A straight BiPO₄ product precipitation was applied in both cycles in presence of 0.05 M H₂SiF₆.

Run 4.—This run was the same as 3, except the by-product precipitates were digested at room temperature for 30 minutes.

TABLE 3

Run	First Cycle			Second Cycle		
	By-product pptn. step, Gamma Factor	Product pptn. step, Gamma Factor	Overall Gamma Factor for 1st Cycle	By-product pptn. step, Gamma Factor	Product pptn. step, Gamma Factor	Overall Gamma Factor for 2nd Cycle
1	27.3	16	437	2.4	43.3	103.9
2	35	22.8	794	1.02	38.7	39.47
3	22	16.3	358	2.21	36.9	81.55
4	38.4	12.7	437	1.5	59.6	89.4

residual fines are complexed or solubilized in a manner that the resultant Pu separated will not be materially contaminated thereby. In other words, the Pu product may be separated as an improved product in that it evidences a higher decontamination factor. The results of the several runs under this example are summarized in the following table:

70

Example IV

In the preceding example the use of fluosilicic acid as a substitute for scavengers was described and the results indicated that the decontamination effected without the scavengers by means of fluosilicic acid alone was of a high order. In accordance with the present example,

75

11

similar runs were carried out to further test the fluosilicic acid substitution for scavengers, the present example distinguishing in that special study was made of the quantity of plutonium recovered. In other words, it was desired to determine whether a high yield of plutonium could be recovered if fluosilicic acid alone were used. The results of the runs in accordance with this example are summarized below:

TABLE 4

Run Nos.	Additions, First Cycle	Additions, 2nd Cycle	dF^1 Thru 2 Cycles	dF^1 Thru further steps	Pu loss, 1st Cyc., per cent	Pu loss, 2nd Cyc., per cent
194-201	Ce-Zr; Ce	Ce-Zr; Ce ($(NH_4)_2SiF_6$)	5.3 5.3	6.7 7.1	3.9 4.0	3.8 .9
202-209	Ce-Zr; Ce-Zr	($(NH_4)_2SiF_6$)	5.7	7.4	4.5	1.5
218-226	($(NH_4)_2SiF_6$)					

¹ dF refers to the logarithm of the decontamination factor.

These runs showed, on the basis of plutonium losses, that fluosilicic acid additions actually reduced the loss of plutonium compared with that experienced in the usual use of scavengers while at the same time giving satisfactory decontamination.

Example V

In accordance with this example, a number of runs were carried out to determine the miscellaneous application of fluosilicic acid addition to other phases of plutonium recovery. Under this example, plutonium containing precipitate was recrystallized both in the presence and absence of fluosilicic acid. Details and results respecting these several runs are summarized below:

Run 1.—The Pu product precipitate was made in a solution of 10 N HNO_3 diluted to 1 N. The solution was heated to 75° C. and H_3PO_4 added (over $\frac{1}{2}$ hour) to make the solution 0.4 M therein; the precipitate was digested at 75° C. for one hour.

Run 2.—In this run Fe^{++} was added to the 10 N HNO_3 solution of product precipitate so that final solution would be 0.03 M in Fe^{++} or Fe^{+++} , or both, and then the solution was processed as in Run 1.

Run 3.—In this run Fe^{++} and H_2SiF_6 were added to the 10 N HNO_3 solution of product precipitate to make a final solution 0.03 M in Fe^{++} or Fe^{+++} , or both, and 0.05 M in H_2SiF_6 . The solution was then diluted to 1 N in HNO_3 and further processed as in Run 1.

Run 4.—In this run Fe^{++} and H_2SiF_6 were added as in Run 3 and the resultant 10 N HNO_3 solution of product precipitate containing this Fe^{++} and H_2SiF_6 added drop by drop to a 0.4 M H_3PO_4 solution at 75° C.

The results of these runs are summarized below:

TABLE 5

Run Number	Fe^{++}/Fe^{+++} M	H_2SiF_6 M	Gamma Factors	Percent of Orig- inal Alphas Present in Recrystallized Product Precipitate
1			1.1	99.5
2	0.03		1.2	100
3	0.03	0.05	5.5	100
4	0.03	0.05	4.4	100

From the results it may be observed that by the presence of fluosilicic acid, not only was all of the plutonium recovered in the recrystallization as evidenced by the alpha count of the recrystallized product, but that the gamma contamination, when the fluosilicic acid was present during the recrystallization of the product, was in some instances less than $\frac{1}{2}$ of that initially present.

Example VI

In accordance with this example another miscellane-

12

ous use of fluosilicic acid or salt was tested, namely the use of a solvent therefrom as a washing medium in certain steps in Pu separation and recovery processes where a water wash had been heretofore used.

In the existing operations product precipitates are frequently washed with water. In the centrifugation of such precipitates, a certain amount of fission activity is carried with the $BiPO_4$ as sludge of Zr, Cb and Si. It was

found that this activity which was not held interstitially in the crystals was readily solubilized by fluoride containing compounds of the present invention. A few runs showed that solutions of $(NH_4)_2SiF_6$ and related compounds are particularly effective solvents. Such salts are advantageous in that they show surprisingly low corrosion rates at 40° C. in concentrations of five moles per liter.

Three portions of an extraction precipitate containing Pu were washed with three equal portions of wash solution in the tests for which the data are shown in Table 6. The precipitate was in contact with each wash solution for thirty minutes before centrifuging.

35 TABLE 6

Treatment	Percent Gamma Activity Removed
3 Water washes	0
3 washes 1 M $(NH_4)_2SiF_6$	21.7

There are numerous other instances where the use of fluosilicic acid may be effective. For example, the equipment in which the various precipitations are carried out may become contaminated with strong activity accumulating on the equipment. It has been found that if such equipment is washed with solutions of fluosilicic acid that this activity may be removed therefrom and the surfaces cleansed.

While it is not desired to be bound by any theory of operation, the following may illustrate to some extent the mechanism of the fluo-type reagent of the present invention for decontaminating.

The efficacy of fluosilicic acid and equivalent compounds as an aid to decontamination may be due to its acting as a reservoir of fluoride ions which form more stable complexes with zirconium, columbium and the various other elements than with silicon. Amounts of such complexed fluoride ion may be introduced into the system which would be prohibitive from the corrosion standpoint, if the fluoride ion were not so complexed. The following equation may be representative of the course of the reaction in, for example, complexing zirconium.

In the above examples, the use of fluosilicic acid has been principally described as this is the specific compound preferred from the industrial standpoint and is a readily available commercial material. However, the use of various derivatives such as ammonium and potassium salts thereof or the use of fluotitanic or other similar

compounds may be employed in a comparable manner. For convenience of description all of these various fluorine containing reagents are designated as fluo-reagents. As has been described, the fluo-reagents may be used in a number of ways varying from assisting the precipitation steps to washing of precipitates and even the washing of equipment in which radioactive materials have been present. By the term 'complexing' or 'solubilizing' there is referred to the action described above of eliminating activity, presumably by rendering soluble elements or materials which cause this activity or constitute a source of the contamination. However, it is not desired to be bound by any theory of operation.

As indicated in the examples a relatively small amount of fluo-reagent such as .05 M usually suffices. However, the invention is not limited in this respect and larger or smaller amounts, as for example, from 0.002 M to 1.00 M may be used. The upper limit of 1.000 M depends on the solubility of the compounds formed by the fluosilicate ions with the bismuth, iron, sodium and other ions present. So long as the limit of solubility is not exceeded, any amount up to 1.000 M may be used. Thus within the broad limits of 0.002 M to 1.000 M, solubility controls and too much fluo-reagent might precipitate the bismuth-fluosilicate, sodium-fluosilicate, etc.

The decontamination accomplished may be determined in accordance with conventional procedure and by means of any of the usual instruments employed in measuring radioactivity. That is, by using a Geiger-Mueller counter or equivalent device, the amount of gamma activity present in a sample may be measured before and after treatment and the amount of activity eliminated by the treatment readily ascertained from this data. The term "decontamination factor" used herein is a comparative value or ratio derived by dividing the count value or average of counts for series of runs before any particular step by that count value obtained after the step. An overall decontamination factor is the value obtained by multiplying together several decontamination factors. The percentage of plutonium present or carried in a sample may be ascertained from the alpha count of the respective materials. In carrying out this invention, it is intended the best technique and equipment usually employed in handling and processing radioactive substances will also be employed in the herein disclosed processes.

It is apparent from the foregoing description that fluo-reagents for the purpose of improving decontamination and product yield, may be employed in connection with the BiPO_4 process with or without scavengers. When used in the product precipitation step of the BiPO_4 process, in which no scavengers were employed in the by-product precipitation step, it has many distinct advantages among which are: the processing time is reduced, the processing is simplified, waste disposal is rendered easier, product yield is increased without an increase in the volume handled, and losses in by-products are reduced.

In fact, the BiPO_4 process, without scavengers and employing fluoreagents is the simplest known process for obtaining product in high yield and free from contamination.

According to the best evidence available, the oxidation state of plutonium secured in solution by the action of the oxidizing agents referred to herein and in cited co-pending application Ser. No. 519,714, now U.S. Patent No. 2,785,951, is greater than four, and the oxidation state secured in solution by the action of the reducing agents referred to herein and therein is no greater than four. It should therefore be understood that, as used herein, " $\text{Pu}^{(o)}$ " and " Pu in the (o) condition (or state)" are both synonymous with "plutonium in an oxidation state greater than four" and " $\text{Pu}^{(r)}$ " and " Pu in the (r) condition (or state)" are both synonymous with "plutonium in an oxidation state no greater than four."

It is to be understood that all matter contained in the above description and examples shall be interpreted as

illustrative and not limitative of the scope of this invention, and it is intended to claim the present invention as broadly as possible in view of the prior art.

Having thus described my invention, I claim:

5. In a carrier precipitation process for the separation and decontamination of plutonium values from contamination comprising uranium-fission-product values, including zirconium and columbium values, associated therewith in an aqueous solution comprising precipitating bismuth phosphate therein to carry plutonium therefrom, the improvement step for selectively removing uranium-fission-product contamination concomitantly carried from the solution superficially upon the bismuth phosphate carrier precipitate, without removing a substantial amount of 10 the plutonium content of the carrier precipitate, which comprises washing the formed bismuth phosphate carrier precipitate with an aqueous solution of a complex fluorine-containing reagent having a structural formula:

where: H is chosen from the group consisting of hydrogen, ammonium, and metallic and metalloid ions, M is a metal atom, F is a fluorine atom, and x and y are whole numbers, to wash said contamination from the precipitate.

- 20 25 30 35 40 45 50 55 60 65
2. A process for the removal from a crystalline bismuth phosphate carrier precipitate of superficial contamination, including zirconium and columbium values, which comprises washing the precipitate with aqueous fluosilicic acid to wash said contamination from the precipitate.

3. In a carrier precipitation process comprising the precipitation of bismuth phosphate in an aqueous nitric acid solution having dissolved therein uranium and uranium-fission-product values, followed by removal of 35 the resulting bismuth phosphate precipitate from its supernatant liquid, the improvement method for mitigating co-precipitation of uranium and uranium-fission-product values during said precipitation of bismuth phosphate and for subsequently separating uranium-fission-product values from uranium values resultingly left remaining in said supernatant liquid after said removal of bismuth phosphate precipitate therefrom, which comprises adding and dissolving into said solution fluosilicic acid, thereupon effecting said bismuth phosphate precipitation in the presence of the added fluosilicic acid in the solution, and, after said removal of bismuth phosphate precipitate, precipitating, from said supernatant liquid, fluosilicate ion of the added fluosilicic acid resulting contained therein, as a fluosilicate salt chosen from the group thereof of consisting of sodium fluosilicate and potassium fluosilicate, to preferentially carry uranium-fission product values from the uranium-containing solution.

4. In a process for the separation and decontamination of plutonium values from uranium and uranium-fission-product values associated therewith in an aqueous solution comprising the carrier precipitation of plutonium from said solution by providing a sufficient concentration of bismuth ions and phosphate ions in said solution to precipitate bismuth phosphate therein, and the subsequent separation and removal of the resulting carrier precipitate, the improvement step for enhancing the decontamination efficacy of the process which comprises adding and dissolving into said solution, prior to said removal of carrier precipitate, a soluble complex fluorine-containing reagent having a structural formula:

where: H is chosen from the group consisting of hydrogen, ammonium, and metallic and metalloid ions, M is a metal atom, F is a fluorine atom, and x and y are whole numbers, the concentration of said reagent in said solution being less than approximately 1 molar.

5. In a process for the separation and decontamination of plutonium values, by carrier precipitation thereof, from uranium and uranium-fission-product values associ-

ated therewith in an aqueous solution by providing a sufficient concentration of bismuth ions and phosphate ions in said solution to precipitate bismuth phosphate therein, the improvement method mitigating co-precipitation of uranium and uranium-fission-product values during said carrier precipitation, which comprises adding and dissolving into said solution, to a concentration less than approximately 1 molar, a soluble complex fluorine-containing reagent having a structural formula:

where: H is chosen from the group consisting of hydrogen, ammonium, and metallic and metalloid ions, M is a metal atom, F is a fluorine atom, and x and y are whole numbers, and effecting said carrier precipitation in the presence of said reagent in solution.

6. In a carrier precipitation process for the separation and decontamination of plutonium values from contamination, including uranium and uranium-fission-product values, associated therewith in an aqueous solution, comprising precipitating bismuth phosphate therein to carry plutonium values therefrom, the improvement method for mitigating co-precipitation of uranium and uranium-fission-product values during said bismuth phosphate carrier precipitation, which comprises adding and dissolving into said solution, to a concentration less than approximately 1 molar, a soluble complex fluorine-containing reagent having a structural formula:

where: H is chosen from the group consisting of hydrogen, ammonium, and metallic and metalloid ions, M is a metal atom, F is a fluorine atom, and x and y are whole numbers, and providing a sufficient concentration of bismuth ions and phosphate ions in the resulting solution to precipitate bismuth phosphate therein.

7. In a carrier precipitation process for the separation of plutonium values from uranium values associated therewith in an aqueous solution comprising precipitating bismuth phosphate therein to carry plutonium values therefrom, the improvement method for mitigating co-precipitation of uranium values during said bismuth phosphate carrier precipitation which comprises adding and dissolving into said solution fluosilicic acid to a concentration less than approximately 1 molar and providing a sufficient concentration of bismuth ions and phosphate ions in the resulting solution to precipitate bismuth phosphate therein.

8. In a carrier precipitation process for the separation and decontamination of plutonium values from contamination comprising uranium-fission-product values, including zirconium and columbium values, associated therewith in an aqueous solution, comprising precipitating bismuth phosphate therein to carry plutonium values therefrom, the improvement method for mitigating co-precipitation of uranium-fission-product values during said bismuth phosphate carrier precipitation which comprises adding and dissolving into said solution fluosilicic acid to a concentration less than approximately 1 molar, and providing a sufficient concentration of bismuth ions and phosphate ions in the resulting solution to precipitate bismuth phosphate therein.

9. In a carrier precipitation process for the separation and decontamination of plutonium values from contamination, including uranium and zirconium, columbium, and barium uranium-fission-product values inherently associated therewith in an aqueous nitric acid solution of neutron-irradiated uranium, comprising providing a sufficient concentration of bismuth ions and phosphate ions in said solution to precipitate bismuth phosphate therein to carry plutonium values therefrom, the improvement method for mitigating co-precipitation of uranium values, and zirconium, columbium, and barium uranium-fission-product values during said bismuth phosphate carrier precipitation, which comprises adding and dissolving

into said solution fluosilicic acid within the approximate range of 0.002 molar to 1 molar, while maintaining said solution at a uranium concentration equivalent to a uranyl nitrate hexahydrate proportion within the approximate range of 10% to 40% by weight thereof, at a temperature within the approximate range of 35° to 85° C., at a nitric acid concentration of approximately normal, and in the presence of said fluosilicic acid therein.

10. In a carrier precipitation process comprising the precipitation, in an aqueous nitric acid solution, of a phosphate of a cation chosen from the group consisting of zirconium and columbium, followed by removal of a major portion of the resulting phosphate precipitate from its supernatant liquid, leaving a minor proportion thereof suspended in the supernatant liquid, and subsequently precipitating bismuth phosphate in said supernatant liquid, the improvement method for solubilizing said suspended phosphate precipitate in the supernatant prior to the bismuth phosphate precipitation and thereby mitigating the co-precipitation thereof during the bismuth phosphate precipitation, which comprises adding and dissolving into said supernatant to a concentration less than approximately 1 molar a soluble complex fluorine-containing reagent having a structural formula:

25

where: H is chosen from the group consisting of hydrogen, ammonium, and metallic and metalloid ions, M is a metal atom, F is a fluorine atom, and x and y are whole numbers, and providing a sufficient concentration of bismuth ions and phosphate ions in said supernatant to precipitate bismuth phosphate therein.

11. In the precipitation of bismuth phosphate as a carrier precipitate from an aqueous nitric acid solution, 35 the method for increasing the crystal size of the formed bismuth phosphate precipitate which comprises adding and dissolving into said solution to a concentration less than approximately 1 molar a soluble complex fluorine-containing reagent having a structural formula:

40

where: H is chosen from the group consisting of hydrogen, ammonium, and metallic and metalloid ions, M is a metal atom, F is a fluorine atom, and x and y are whole numbers, and providing a sufficient concentration of bismuth ions and phosphate ions in said solution to precipitate bismuth phosphate therein.

12. In a carrier precipitation process for the separation and decontamination of plutonium values from contamination, including uranium and uranium-fission-product values, associated therewith in an aqueous solution, comprising precipitating bismuth phosphate therein to carry plutonium values therefrom, the improvement method for mitigating co-precipitation of uranium and uranium-fission-product values during said bismuth phosphate carrier precipitation, which comprises adding and dissolving into said solution a soluble complex fluorine-containing reagent chosen from the group consisting of fluosilicic, fluostannic, and fluotitanic acids to a concentration less than approximately 1 molar, and providing a sufficient concentration of bismuth ions and phosphate ions in said solution to precipitate bismuth phosphate therein.

13. In a process comprising precipitating bismuth phosphate in an aqueous solution contaminated with uranium-fission-product values, the improvement method for removing uranium-fission-product contamination concomitantly carried from solution by the bismuth phosphate precipitate, which comprises dissolving said bismuth phosphate precipitate in acid, recrystallizing bismuth phosphate by reducing the acidity of the resulting solution, adding phosphoric acid and a soluble complex fluorine-containing reagent having a structural formula:

70

where: H is chosen from the group consisting of hydro-

gen, ammonium, and metallic and metalloid ions, M is a metal atom, F is a fluorine atom, and x and y are whole numbers, said reagent being present in a concentration less than approximately 1 molar, thereby leaving uranium-fission-product contamination in the complex-reagent-containing supernatant solution.

14. In a carrier precipitation process for the separation and decontamination of plutonium values from contamination comprising uranium-fission-product values associated therewith in an aqueous solution, comprising precipitating bismuth phosphate therein to carry plutonium values therefrom, the improvement method for removing uranium-fission-product contamination concomitantly carried from solution by the bismuth phosphate carrier precipitate which comprises dissolving said bismuth phosphate precipitate in acid, recrystallizing bismuth phosphate by reducing the acidity of the resulting solution, adding phosphoric acid and a soluble complex fluorine-containing reagent having structural formula:

where: H is chosen from the group consisting of hydrogen, ammonium, and metallic and metalloid ions, M is a metal atom, F is a fluorine atom, and x and y are whole numbers, said reagent being present in a concentration less than approximately 1 molar, thereby recarrying plutonium values with the recrystallized carrier precipitate while leaving uranium-fission-product contamination in the complex-reagent-containing supernatant solution.

15. The process of claim 14 wherein said soluble complex-fluorine-containing reagent is fluosilicic acid.

16. In a carrier precipitation process for the separation and decontamination of plutonium values from contamination comprising uranium-fission-product values, including zirconium and columbium values, associated therewith in an aqueous solution, comprising precipitating bismuth phosphate therein to carry plutonium values therefrom, the improvement method for removing uranium-fission-product contamination concomitantly carried from solution by the bismuth phosphate carrier precipitate which comprises dissolution of said bismuth phosphate carrier precipitate in substantially 10 normal nitric acid followed by recrystallization thereof by means of: incorporation of fluosilicic acid into the resulting solution to a concentration no greater than approximately 1 molar, dilution thereof to substantially one normal in nitric acid, and incorporation of phosphoric acid therein; thereby recarrying plutonium values with the recrystallized carrier precipitate while leaving uranium-fission-product contamination in the fluosilicic-acid-containing supernatant solution.
